UNITED STATES PATENT OFFICE.

FELIX LEE GAY, OF SAN BENITO, TEXAS.

WATER GATE.

Application filed March 31, 1921. Serial No. 457,396.

To all whom it may concern:

Be it known that I, FELIX L. GAY, a citizen of the United States, residing at San Benito, in the county of Cameron and State 5 of Texas, have invented certain new and useful Improvements in Water Gates, and I do declare the following to be a full, clear, and exact description of the invention, such as will enable others skilled in the art to 10 which it appertains to make and use the same.

This invention relates to an improved water gate for use in irrigating ditches and the like, and one object of the invention is 15 to provide a gate which may be positively guided in its downward movement to a closed position and which may be firmly held in a closed position.

Another object of the invention is to provide a water gate which will be limited in 20 its downward movement and further provide a gate which will be braced against water pressure and thus prevented from being bent out of shape and prevented from 25 feeding properly.

Another object of the invention is to provide a gate which will be comparatively simple in construction and very easy to operate.

30 This invention is illustrated in the accompanying drawings, wherein:

Figure 1 is a view showing the improved gate in front elevation.

Figure 2 is a side elevation of the im- 35 proved gate.

Figure 3 is a vertical sectional view taken along the line 3—3 of Fig. 1.

Figure 4 is a view in front elevation showing a modified form of gate.

40 Figure 5 is a vertical sectional view taken along the line 5—5 of Fig. 4.

Figure 6 is a transverse sectional view taken along the line 6—6 of Fig. 4.

This improved gate is to be placed in an 45 irrigating ditch and for a shallow ditch will be constructed as shown in Figs. 1, 2 and 3. This gate shown in Figs. 1, 2 and 3 is provided with a body plate 1, the side edge portions of which will be bent inwardly 50 to provide guiding flanges 2 and the lower end portion of which will be bent upwardly to provide a trough 3 having its edge portions bent outwardly to provide a lip 4 which lip serves as a guide. An opening 55 is formed in this plate above the trough 3 and between the flanges 2 so that water

may pass through this plate into the pipe 5. In forming the opening which is to receive the pipe, the metal of the plate will be cut to provide tongues 6 which will extend along 60 the pipe 5. Rivets 7 are passed through these tongues 6 and through the pipe so that the pipe will be securely held in place.

The gate or door 8 is also formed from a heavy plate of sufficient width to fit 65 against the plate 1 with its side portions engaged by the side flanges 2 of the frame. The lower end portion of this plate which forms the gate 8 is bent upwardly against the face of the gate as shown at 9 to 70 strengthen the gate and is then bent outwardly to provide a strip 10 which will serve to strengthen the plate against bending. It should be further noted that when the gate is in the lowered position, the guiding strip 4 may engage the edge of the bracing strip 10 and thus serve to provide pressure which would hold the plate 8 in tight engagement with the plate 1 and end of the pipe 5. A handle 11 is connected with the 75 upper end portion of this gate 8 and if desired, the upper end portion of the gate may be turned over as shown at 12 so as to strengthen the upper end portion of this plate. When this form of gate is in use, it 80 will be set in the ditch and may be anchored by being embedded in cement or may be secured in a vertical position across the ditch by any suitable means. When it is desired to have water pass through the pipe 5, it 85

is simply necessary to grasp the handle 11 and draw the gate upwardly to a raised position. When it is desired to shut off the passage of water through the pipe, the handle will again be grasped and the gate shoved 90 downwardly. The gate will be guided in its downward movement by the flanges 2 and will be braced against bulging under water pressure by the flange or strip 10. The lower edge by being turned will be strengthened and can thus readily cut through small sticks which may have lodged above the trough 3. If the lower edge of the gate should extend from the plate 1 a sufficient amount to normally cause it to miss the 95 trough, the lower edge of the plate will strike the guiding strip 4 and thus the plate will be guided down into the trough. When the gate is shoved tightly into the closed position, the edge of the bracing strip will 100 engage the face of the guiding stripe 4 and thus pressure will be applied which will tend 105 to hold the gate in the closed position. The 110

to force the plate 8 toward the plate 1 and thus provide a very tight closure.

In Figs. 4, 5 and 6 there has been shown a gate for use in connection with relatively 5 deep ditches. In this form, the major portion of the structure shown in Figs. 1, 2 and 3 will be made use of, the only difference being that instead of providing a handle 11 there will be provided a bar 13 and the 10 frame 1 will be placed between the side bars 14 and secured by rivets or other similar fasteners. These side bars are formed of angle iron and have their upper ends connected by a cross bar 15 which will also be 15 formed of angle iron. Corner plates 16 are put in place as shown clearly in Fig. 4 and secured to the side bars and cross bar by rivets so that the cross bar and side bars will be securely connected and held against 20 movement. A guiding strap 17 is secured to the depending flange of the cross bar 15 and the cross bar and guiding strap will be provided with aligned openings 19 and 20 for receiving a securing pin passed 25 through these openings and through one of the openings 21 formed in the operating bar 13. When this form of gate is used, it will be mounted in the ditch after the manner set forth in connection 30 with the gate disclosed in Figs. 1, 2 and 3 and by passing the securing pin through the openings 19 and 20 and one of the openings 21, the gate can be securely held either in a closed position or in a raised position. It 35 will be further noted that the openings 21 through which the pin will pass when the gate is in the raised or open position, are

placed in the bar 13 so that the gate may be held entirely open or only partly open.

I claim:

1. A water gate comprising a body plate having a water passage and having its lower end portion bent upwardly to provide an outer wall of a trough, the outer wall of the trough being bent to provide an outwardly and upwardly inclined lip, and a closure plate held in sliding engagement with said body plate and having its lower end portion bent upwardly upon itself to provide a reinforced lower edge for entering 45 said trough and then bent outwardly to provide an outstanding rib for bracing the closure plate against bulging and for engaging said lip and holding the closure plate in tight closing position, said lip further serving to guide the lower end of the closure plate into said trough.

2. The structure of claim 1, and a frame having side bars connected with and extending above said body plate, a cross bar extending between the upper end portions of said side bars, and an actuating bar carried by the closure plate for moving the closure plate vertically and provided with fastener receiving openings for registering with a fastener receiving opening in the cross bar whereby a fastener may be passed through aligned openings to hold the bar against movement with the closure in an adjusted position.

In testimony whereof I have hereunto set my hand.

FELIX LEE GAY.
